(57) **CLAIM**

The ornamental design for an electronic cigarette rod, as
shown and described.

DESCRIPTION

FIG. 1 is a perspective view of an electronic cigarette rod
according to a first embodiment of the present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of an electronic cigarette rod
according to a second embodiment of the present design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines on the electronic cigarette rod illustrate
portions of the article and form no part of the claimed
design.

1 Claim, 11 Drawing Sheets
